United States Patent Office.

I. STONE LISTER, OF PHILADELPHIA, PENNSYLVANIA.

Letters Patent No. 79,288, dated June 23, 1868.

IMPROVED AXLE-BOX.

The Schedule referred to in these Letters Patent and making part of the same.

TO ALL WHOM IT MAY CONCERN:

Be it known that I, I. STONE LISTER, of Philadelphia, Pennsylvania, have invented certain Improvements in Axle-Boxes; and I do hereby declare the following to be a full, clear, and exact description of the same.

My invention consists in chambering the bearing of an axle-box so as to form, above the journal, a reservoir for oil, which passes by its own gravity through channels in the bearing to the journal, the flow of oil from the reservoir being regulated by a screw-valve, all as described hereafter.

The object of my invention is to effectually lubricate the bearing, and at the same time economize the consumption of oil.

In order to enable others skilled in the art to make and apply my invention, I will now proceed to describe its construction and operation, reference being had to the accompanying drawing, which forms a part of this specification, and in which—

Figure 1 is a vertical sectional view of my improved axle-box.

Figure 2, a transverse section on the line 1-2, fig. 1.

Figure 3, a section on the line 3-4, fig. 1.

Figure 4, a sectional plan view on the line 5-6, fig. 1.

Figure 5, a detached view, drawn to an enlarged scale, and illustrating a portion of my invention; and

Figure 6, an inverted plan view of the journal-bearing.

A is the top, B the bottom, C the front, and D the back of an axle-box of the shape, or approximating to the shape shown in the drawing.

In the back D is the usual circular opening for the admission of the end of the axle, and extending vertically through the back, from the top to the bottom of the same, is an opening, *a*, into which are inserted (above and below the axle) strips of leather packing, *b* and *b'*.

A yoke, *E*, extends through the opening *a*, on each side of the packing, and passes beneath the strip *b'*, the latter being raised and maintained in contact with the under portion of the axle, on raising the said yoke, by means of its nuts *c c*.

The upper packing-strip *b'*, which rests upon the axle, is prevented from rising by the nuts *c c*, which bear upon its upper edge, and is prevented from moving laterally by a pin, *d*, which extends across the opening *a*, and passes through a slot, *d'*, in the strip, (see fig. 3.)

The journal-bearing or brass, *F*, is introduced through an opening, *i*, in the top, and through the front of the box, after removing the sliding door *e*; and the said bearing is held in its place, and prevented from moving either longitudinally or laterally, by a projection, *f*, on the top, and by projections *g g* at the sides of the box, (see figs. 1 and 4.)

The opening *i*, above mentioned, extends across the top of the box, and is covered by an oil-reservoir, *G*, of the square or rectangular form shown in the drawing, the latter being secured to the box by bolts *j j*, fig. 2, and having a hollow projection, *k*, screwed into the top of the journal-bearing *F*.

Extending through the bearing, and communicating with the hole in the projection, *k*, of the reservoir, is a channel, *l*, in the bottom of which are three or more holes, *m*, through which, under the circumstances described hereafter, the lubricating-material from the reservoir passes to the journal; and each of these holes communicates with a diagonal groove, *n*, in the under face of the bearing, as shown in fig. 6.

In the top of the reservoir, *G*, fig. 5, is a screw-plug, *I*, on removing which the reservoir may be filled; and extending through the said plug, and communicating with each other, are a vertical and a horizontal passage, *p* and *p'*, for the supply of air to the reservoir, which supply, however, may be cut off, to a greater or less extent, by raising or lowering a screw or screw-valve, *q*, which passes through the top of the plug.

In axle-boxes as heretofore constructed, the bottom of the box has served as a receptacle for the oil or other lubricating-material to be supplied to the journal, and the packing in the back of the box has been arranged with a view of preventing leakage of the lubricating-material.

By this arrangement, when the reservoir is filled, more lubricating-material is supplied to the journal and its bearing than is required, and a portion of it is wasted or lost by leakage; and when the supply becomes low in the reservoir, the journal is not properly and regularly oiled, if at all.

These objections I overcome by the use of my invention, in which, as I will now proceed to describe, a proper and constant supply of lubricating-material is fed to the journal from above, instead of from below.

The oil contained in the reservoir, G, flows through the passage in the screwed projection k, into the channel l of the bearing, and thence through the holes m m m into the grooves n, from which it is fed to the journal, the supply of air to the reservoir, and consequently the flow of oil from the same, being regulated by the screw-valve q, fig. 5. If the latter be raised, communication between the passages p and p' will be opened, air will enter the reservoir G, and the oil will flow freely from the same to the journal; but if the screw-valve be closed, and the supply of air shut off, the oil cannot flow from the reservoir without producing a partial vacuum, and will therefore remain within the same. It will thus be seen that, by adjusting the screw-valve q properly, the flow of oil can be regulated to a nicety, and no more nor less than the proper quantity fed to the journal.

In some cases the reservoir G may be dispensed with, and a receptacle for oil formed in an enlargement of the channel l, or in a projecting portion of the bearing, the screw-plug I and its valve being then applied to the bearing instead of to the reservoir G.

The diagonal grooves n n n of the bearing prevent the clogging of the passages m, and insure an equal distribution of the lubricating-material over the surface of the journal.

The only office of the packing-strips b and b' in this case is to prevent the admission of particles of dust to the interior of the box, and the consequent clogging of the grooves n and passages m.

I claim as my invention, and desire to secure by Letters Patent—

1. A bearing, arranged within an axle-box, above a journal, and having a chamber and channels leading from the same, through which oil may flow by its own gravity to the journal, all substantially as and for the purpose described.

2. The combination of the said chambered bearing with the oil-reservoir G.

3. The plug I, with its air-passages p and p', and regulating-valve q, in combination with the reservoir G. In testimony whereof, I have signed my name to this specification in the presence of two subscribing witnesses.

I. STONE LISTER.
